[57] CLAIM

The ornamental design for a beverage can holder, as shown and described.

DESCRIPTION

FIG. 1 is a perspective view of a beverage can holder showing our new design;

FIG. 2 is a right side elevational view with the left side being a mirror image thereof;

FIG. 3 is a front elevational view thereof;

FIG. 4 is a rear elevational view thereof;

FIG. 5 is a top view thereof;

FIG. 6 is a perspective view of an alternate embodiment of FIG. 1;

FIG. 7 is a right side elevational view of FIG. 6, the left side being a mirror image;

FIG. 8 is a front elevation view of FIG. 6;

FIG. 9 is a rear elevational view of FIG. 6; and,

FIG. 10 is a top plan view of FIG. 6.

The undisclosed bottom view of both embodiments is unornamented. The broken lines showing the can in FIGS. 1 and 6 and the advertisement flag in FIGS. 2 and 3 are for illustrative purposes only and form no part of the claimed design.
